UNITED STATES PATENT OFFICE.

DAVID T. PUNCH, OF CHICAGO, ILLINOIS, ASSIGNOR, BY MESNE ASSIGNMENTS, TO CHICAGO MOP & POLISH COMPANY, OF CHICAGO, ILLINOIS, A CORPORATION OF ILLINOIS.

MOP.

1,158,846.

Specification of Letters Patent.

Patented Nov. 2, 1915.

Application filed March 13, 1915. Serial No. 14,123.

To all whom it may concern:

Be it known that I, DAVID T. PUNCH, a citizen of the United States, residing at the city of Chicago, county of Cook and State of Illinois, have invented certain new and useful Improvements in Mops, of which the following is a specification, reference being had to the accompanying drawings, forming a part thereof.

10 This invention relates to certain new and useful improvements in mops, the objects of my present invention being to provide a mop of few, simple, cheap, and economically manufactured parts which may be compactly arranged for storage or shipment and which may be readily and quickly operatively assembled; to provide a mop in which the body-portion of yarn or other fabric is easily detachably fastened to the head of the mop,

15 so that, in case of wear, the body-portion may be at once renewed; to provide a mop in which the handle and head of the mop are so attached together that the handle may be adjusted to and held at practically any angle relatively to the head, whereby the head of the mop may conveniently, for cleaning purposes, reach under beds, chairs, and the like, or into corners or other out of the way places; and to improve generally upon, and

20 simplify the construction of, mops of the class described.

With the above and other objects in view, my present invention resides in certain novel features of form, construction, arrangement, and combination of parts, all as will hereinafter be described and afterward pointed out in the claims.

In the accompanying drawings, which show my invention in preferred form, Figure 1 is a perspective view, partly broken away, of a mop embodying my invention; Fig. 2 is an elevational view of the mop with the body-portion thereof omitted, showing the mop-head in transverse section and one of the handle-engaging members or plates in longitudinal section; and Fig. 3 is a plan view of the member or bar usable in my new mop for detachably fastening the mop-body to the mop-head.

50 Referring to the said drawings, in which like reference characters refer to like parts throughout the several views, A indicates the mop-head, which is made up of or comprises two flat preferably metallic plates 1

and 2 rigidly fixed flatwise together. Preferably, in fixing said plates together, lower plate 2 is first suitably perforated, as at 3-3 (see particularly Fig. 2), and then material of upper plate 1 is punched or otherwise driven through such perforations 3 and 60 upset, as at 4, upon the under face of lower plate 2, plates 1 and 2 being thereby riveted together. Plates 1 and 2, which are preferably triangular in shape in plan view, are oppositely rounded or dished at their marginal edge to flare laterally, as at 5 and 6, respectively, the head being thereby formed or provided with a circumferential mop-body receiving-groove 7 extending preferably continuously therearound. Riveted, as 70 shown, or otherwise rigidly fixed to head A preferably in the center thereof, is an upstanding short member or stem 8 provided preferably integrally with a spherical extension or ball 9.

B indicates a suitable preferably wooden pole adapted to form the handle of the mop, pole B being shown broken away, but which may be of any proper length, as may be desired. Adjacent its lower end, pole or 80 handle B is provided with a circumferential groove 10, for purposes hereinafter appearing.

Engaging pole B at its lower end is a pair of oppositely-disposed elongated plates 85 11-11' approximately semi-cylindrical in cross-section, which plates 11-11' are provided, respectively, with spherically concaved extensions 12-12' adapted to engage with spherical member or ball 9 and forming with ball 9 a ball-and-socket joint between head A and handle B, whereby handle B may be readily adjusted and held, in the use of the mop, at practically any angle relatively to head A, so that head A may 95 conveniently reach under beds, chairs, and the like, or into corners and other out of the way places. Extending transversely of and through plates 11-11' intermediate their said extensions 12-12' and the lower end of 100 pole B, as shown especially in Fig. 2, is a threaded bolt or the like 13 adapted to receive a suitable preferably wing-nut 14 to detachably maintain plates 11-11' and their said extensions 12-12' in operative 105 engagement with pole B and spherical member or ball 9. Plates 11-11' are also each provided preferably at or adjacent their up-

per end with an inwardly-projecting lug 15 adapted to fit in and engage with groove 10 to firmly and positively prevent the withdrawal or removal of handle or pole B from 5 between said plates 11—11' when the same are in operative engagement therewith.

C indicates the mop-body, which comprises a tubular casing 16 of fabric or other suitable flexible material, a plurality of 10 strands of yarn or other suitable fabric 17 fixed to and projecting from casing 16, and an elongated metallic bar 18 fitting lengthwise in casing 16, mop-body C, and particularly its casing 16 with bar 18 therein, being 15 also preferably triangular in shape in plan view to correspond with head A. It is, of course, to be understood that, in the manufacture of mop-body C, casing 16 with its strands 17 is extended lengthwise to receive 20 bar 18 and then, with bar 18 therein, bent to assume its operative triangular shape to fit head A, casing 16 with its head-engaging bar 18 being adapted to fit in said groove 7 of head A, as shown particularly in Fig. 1. 25 At its ends, bar 18 is suitably perforated to removably receive a cotter-pin or other suitable member 19 to detachably fasten the ends of bar 18 together and thereby the mop-body C removably upon head A.

30 I am aware that minor changes in the form, construction, arrangement, and combination of the several parts of my new mop may be made and substituted for those herein shown and described without departing 35 from the nature and principle of my invention.

Having thus described my invention, what I claim and desire to secure by Letters Patent is:

40 1. In a mop, the combination with a handle cylindrical at one end, said handle being provided transversely at its said end with a circumferential groove, of a pair of oppositely disposed elongated head-engaging

members lengthwise fitting smoothly upon 45 the peripheral face of said handle at its said end, each of said members being approximately semi-cylindrical in cross-section, a bolt transversely engaging only the shanks of said members below the said end of said 50 handle for clampingly securing said members in frictional engagement with said handle, and integral arc-shaped lugs on said members, said lugs fitting in and engaging with the walls of said groove to prevent endwise 55 removal of said handle from between said members.

2. In a mop, the combination with a head provided with an approximately spherical member, of a handle cylindrical at one end, 60 said handle being provided transversely at its said end with a circumferential groove, a pair of oppositely disposed elongated plates lengthwise fitting smoothly upon the peripheral face of said handle at its said end, 65 each of said plates being approximately semi-cylindrical in cross-section, oppositely-disposed spherically-concaved extensions on said plates, said extensions fitting upon said member and forming therewith a ball-and-socket joint between said head and said handle, a bolt transversely engaging only the shanks of said plates intermediate the said 70 end of said handle and said extensions for clampingly securing said extensions in engagement with said head and said plates in frictional engagement with said handle, and integral arc-shaped lugs on said plates, said lugs fitting in and engaging the walls of 75 said groove for preventing endwise removal 80 of said handle from between said plates.

In testimony whereof, I have signed my name to this specification, in the presence of two subscribing witnesses.

DAVID T. PUNCH.
